UNITED STATES PATENT OFFICE.

ERNEST E. LAUN AND ROY E. TULLGREN, OF CHICAGO, ILLINOIS.

GAS GENERATOR.

Application filed November 30, 1925. Serial No. 72,187.

To all whom it may concern:

Be it known that we, ERNEST E. LAUN and ROY E. TULLGREN, citizens of the United States, residing in Chicago, in the county of Cook, in the State of Illinois, have jointly invented certain new and useful Improvements in a Gas Generator, of which the following is a specification.

The invention relates to gas generators and particularly to that type of these devices which are designed to transform a volatile liquid such as gasoline into a fluid capable of consumption for heating purposes.

15 The invention has among its various objects the provision of an arrangement including a reservoir or carburetor in which the liquid is confined and to connect a motor fan therewith whereby air is introduced to the carburetor and a gaseous fluid is exhausted therefrom and to combine with a structure such as this a means whereby the operation of the blower fan is controlled by the pressure contained in a receptacle to 25 and from which the fluid is supplied.

30 The invention has an additional object the provision of an arrangement whereby the blower fan is rendered inoperative in the event that the pressure in the receptacle is reduced below a pressure required for the normal operation of the device.

35 The invention also has as an object, the provision of an arrangement whereby the fluid pressure in said above mentioned receptacle is released when said pressure exceeds a certain amount.

40 The invention has as another feature the employment of an arrangement whereby air is supplied to the fluid drawn from the carburetor and to combine a valve with this arrangement whereby the amount of air and fluid may be combined to result in the proper mixture for consumption.

45 It is also an object of the invention to employ a receptacle into and from which the gas is supplied having a movable element for actuating the elements above described operable by the pressure in the receptacle and to provide a liquid seal between the receptacle and said element.

50 It is also a feature of the invention to provide a means whereby the escape of fluid from the receptacle is prevented into certain passages leading to the carburetor and fan.

55 The invention has these and other objects all of which will be explained and more

readily understood when read in conjunction with the accompanying drawings which illustrate one embodiment of which the invention is susceptible it being obvious that changes and modifications may be resorted to without departing from the spirit of the appended claims forming a part thereof.

60 Fig. 1 is a side elevation of a device constructed according to one embodiment of the invention and having a reservoir associated therewith.

65 Fig. 2 is a vertical central sectional view of one of the elements employed in the structure illustrated in Fig. 1.

70 Fig. 3 is an enlarged view of a switch box carried by the structure illustrated in Fig. 2 and employed for controlling the motor fan whereby pressure is provided in the various elements shown in Fig. 1.

75 Fig. 4 is a sectional plan view of the device shown in Fig. 3.

80 Fig. 5 is a view taken on line 5—5 of Fig. 3 showing more in detail one of the elements of the switch.

85 Fig. 6 is a sectional view of a mercury valve employed in the structure.

Fig. 7 is a sectional view of a mixing valve utilized in the device.

Fig. 8 is a sectional view of a fragment of the device shown in Fig. 2, and

Fig. 9 is a side view of the motor and fan of the device.

90 Like numerals of reference refer to corresponding parts throughout the different views of the drawings.

95 In the embodiment of the invention as illustrated in the drawings the use of a reservoir 10, is contemplated which may be imbedded in the ground or stored at a place remote from other portions of the device so that it may be filled without inconvenience to the occupant of the premises in which other portions of the device are located.

100 This reservoir 10 has located therein a box like structure 11, which is open at one side and is provided with a number of parallel arranged rods 12, and 13, arranged transversely to the box 11, upon which a web 14, of some suitable fabric, such as burlap, is supported. Pipe connections 15, and 16, extend from the reservoir 10, the pipe 15, being connected with a blower fan 17, and provides a passage from the blower to the reservoir to create a pressure therein which causes the gases emanating from the web

14, to be forced from the reservoir through the passage 16. The passage 15, is provided with a tubular extension 18, having a hand wheel 19, secured thereto which is formed with a cap for closing the end of this extension. Another tubular element 20, projects from the reservoir into the path of rotation of the hand wheel and provides a vent for the reservoir when the latter is being filled.

10 This last mentioned tubular element 20, is provided with a cap 21, which must be removed from the element 20, before the hand wheel 19, can be rotated to remove the 15 cap from association with the tubular extension 18.

16 The fan 17, has an air intake pipe 22, and is provided with a pipe connection 23, which is connected with a mercury valve 24. 20 The pipe extension 23, is connected with a branch 25, and is also connected with a tubular element 26, which connects with the air pipe 15, leading to the reservoir or carburetor, generally designated 10. A mercury valve 27, is located between the tubular extensions 25, and 26, thus it is evident that as the fan is rotated, air will be driven through the tubular extension 23, valve 24, and a portion thereof will pass through the 25 tubular extension 25, and another portion thereof will pass the mercury valve 27, and travel through the tubular extension 26, and through the pipe connection 15, to the reservoir 10, creating a pressure therein which 30 is allowed to escape from the reservoir or carburetor through the tubular passage 16, and through the regulating valve 28. This regulating valve 28, is shown in detail in Fig. 7.

40 The motor fan 17 includes a motor and a fan which are arranged in separated relation to each other so that one is remote from the other.

45 This arrangement is resorted to to prevent the possibility of causing injury to these elements by ignition of gas by sparking of the motor should the pressure at any time be in excess of that capable of control by the mercury valve. As an example should pressure be developed in the carburetor in excess of that controlled by the mercury valve 24, the arrangement is such that this gas would pass said valve and travel through the fan housing and thence to the atmosphere via the pipe 22 which may terminate outside of the building in which the device is located, and thereby prevent ignition of this gas, which might occur if the motor were located in close proximity to the fan.

55 60 From the foregoing, it is evident that a mixture of gas and air passes the valve 28, and by virtue of the fact that this valve is connected by means of the tubular passage 29, to the receptacle 33, combustible gas under pressure is delivered to the receptacle.

This tubular passage 29, has connected thereto an upwardly extending tubular passage 31, which is arranged within the receptacle 30, and extends upwardly a suitable distance in the receptacle 30. The 70 receptacle 30, is provided with a suitable amount of liquid 32, and also has arranged therein a pressure actuated gasometer 33. The lowermost end of the gasometer 33, is open and is sealed through the medium of 75 the liquid 32. As before stated, this gasometer 33 is movable within the receptacle 30, and the liquid 32, it being actuated in one direction by the pressure existing in the space 34, provided between the level of the 80 liquid 32, and the walls of the gasometer 33.

85 It is of course understood that the pressure existing in the space 34, is caused to exist therein by virtue of the tubular extension 31, which extends a suitable distance above the normal liquid level of the liquid 32, and discharges the gas into the space 34. As the pressure in the space 34, increases, the gasometer 33, is elevated, when the latter reaches a certain predetermined elevated position, the switch structure, generally designated 35, and clearly shown in Figs. 3, and 4, is actuated to cut out the motor of the fan 17, and prevent its further operation.

90 A tubular extension 36, communicates with the space 34, and is provided to form a means whereby the gas in the space 34, is permitted to escape therefrom into a feed pipe 37, which is connected to a burner of a stove or furnace. As the pressure in the space 34, is reduced through consumption of the gas passing from the tubular member 36, the gasometer 33, is automatically lowered. When the gasometer is lowered to a certain predetermined position, the switch mechanism, 100 generally designated 35, is again actuated to cause the operation of the motor fan 17, which will again build up the pressure in the space 34, and cause the gasometer 33, to again be elevated until the switch mechanism 105 35, is again actuated to cut out the motor of the fan 17. A means is provided whereby when a pressure beyond a predetermined amount exists in the space 34, this pressure 110 may be relieved and thereby prevent injury to the various elements forming the structure, or the dwelling in which the device is located.

115 This last mentioned means includes a tubular passage 38, which may be termed a "blow-off passage," and be extended to some point outside of the structure in which the device is located so that the excess pressure in the space 34, may be exhausted into the atmosphere.

120 125 To prevent blowing up of the structure due to an excess of the pressure in the space 34, the tubular element 38, is provided with an extension 39, having the apertures 40. The tubular extension 39, extends through the gasometer 33, the latter of which is pro-

vided with a tubular portion 41, within which the extension 39, is located. The tubular portion 41, of the gasometer 33, is provided with a plurality of apertures 42, which 5 when the pressure in the space 34, exceeds a predetermined amount, causes the gasometer 33, to be elevated until the apertures 42, in the tubular portion 41, thereof to register with the apertures 40, provided in the tubular extension 39, and will thus allow the escape 10 of the pressure and prevent injury to the device.

Provision is made to allow the escape of any gas which might find its way into the 15 space between the upper end of the gasometer and the receptacle 30, in which the gasometer operates. To this end the pipe 39, is open at its upper end and supported at this end in spaced relation to the cover of 20 the receptacle by means of a spider 39', thus, any gas finding its way into the space in which the gasometer operates, may escape through the pipe 39 and be discharged into the atmosphere through the blow-off pipe 38. 25 The gasometer 33, is provided with an apertured lug 43, which as clearly shown in Fig. 8, is connected with an arm 44, which extends through an aperture 45, in the receptacle 30, and is mounted upon a shaft 46, 30 the shaft being a part of the switch mechanism, generally designated 35, and clearly shown in Figs. 3 and 4.

The end of the arm 44, adjacent the shaft 46, is encased in a housing 47, which is secured to the receptacle 30, and provides a closure for the opening 45. This housing 47, is as shown in Fig. 4, sealed or closed by means of a packing nut 48.

The switch mechanism, generally designated 35, is provided with a means, generally designated 49, which is operable in the event of the pressure in the space 34, being reduced beyond the predetermined reduced pressure previously referred to, or otherwise, to thereby 45 cut out the motor and prevent its further operation until again manually brought into service.

The switch, generally designated 35, includes a shaft 50, which is rotated through 50 the medium of the arm 44, and its connection with the gasometer 33, and this shaft carries a forked-arm 51, having rollers 52-52, which engage an extension 53, of a snap switch 54. This snap switch 54, is of the ordinary character such as now extensively used and therefore will not be described in detail.

It being understood that this switch is connected with a source of current and in turn 60 connected with the motor of the fan 17, and also with switch 49.

It is further obvious that as the shaft is rotated upon the downward movement of the gasometer 33, the forked-arm 51, will cause

the operation of the switch to throw in the 65 motor and cause its actuation.

It is further evident that as the gasometer 33, is elevated, the shaft 50, will be rotated in the reverse direction, which causes the switch to be actuated to cut out the motor 70 and to stop its rotation when the gasometer reaches a certain predetermined elevation. During the operation of the structure, this intermittent throwing on and off of the motor, will cause proper pressure to be 75 maintained in the space 34, during consumption of the gas contained in the space 34.

The switch element, generally designated 49, is provided to prevent the accidental discharge of fuel through the burner, should at any time the current leading to the motor be cut off for an unreasonable period, as it is evident that should a condition such as that just referred to at any time exist, that a burner might be left open, and due to the consumption of the fuel existing in the space 34, become extinguished and would therefore, unless some provision is made for automatically preventing the operation of the motor, cause the pressure to again be produced in the space 34, and escape through the open burner. To obviate any happenings such as this, the shaft 50, of the switch is provided with a lifting element 55, which is designed to co-operate with a holding dog 56, which is actuated in one direction by a coil spring 57, which reacts between the dog and a wall of the casing in which the switch, generally designated 35, is located. The holding dog 56, engages a switch blade 58, pivoted at 59, and operable by means of the spring 60, to cause the disengagement of the switch blade 58, with the contact element 61, upon the actuation of the holding dog 56, by the element 55.

The switch blade 58, is normally held closed, and is, through the medium of the conductors 62, and 63, connected in circuit with the motor.

From the explanation of the construction and the operation of the switch, generally designated 49, it is manifest that when the gasometer 33, is lowered beyond the predetermined lowered position, previously referred to, that the element 55, will be brought into engagement with the holding element 56, and cause the latter to be rocked on its pivot 64, to release the spring actuated switch blade 58, from its connection with the terminal 61, which will thus cut out the motor and prevent its operation to build up a pressure in the space 34, which might under the conditions previously referred to, escape through an open burner without being consumed.

A push button 65, is located so that it may co-operate with the switch blade 58, and

cause the latter to be moved to a position in which it co-operates with the holding element 56, and the terminal 61.

The valve shown in Fig. 7, is provided with a lever 28' whereby the valve portion 66, thereof may be rotated to control both the passage of combustible fluid passing from the pipe 16, and the air fed to the valve from the pipe 25, which are mixed together in proper proportion and discharged into the space 34.

The mercury valves 24, and 27, employed in the structure, are shown in detail in Fig. 6 and are formed with a chamber 67, in which mercury may be confined, and in addition, are provided with a valve element 68, the structure being such that it will permit the passage of gas in one direction and prevent the escape of gas in the reverse direction, thus when the operation of the motor ceases, the pressure existing in the space 34, is maintained until reduced by consumption.

It is evident from the construction of the valve shown in Fig. 6, that, as the back pressure is increased, the float valves 68, will be acted upon by the pressure to move the float toward the seat 68' causing it to become seated thereon, which with the mercury provides a double seal against the escape of the gas under pressure from the space 34.

From the foregoing explanation of the construction and operation of the device, it is manifest that a simple arrangement is provided whereby a pressure producing means such as the motor fan 17, is automatically and intermittently actuated to maintain a predetermined pressure in the space 34, between the gasometer and the receptacle 30.

It is further evident that a means is provided for preventing the accidental operation of the motor fan 17, to build up a pressure should at any time the current leading to the motor be cut off and the pressure of the fuel reduced and the fuel consumed thus eliminating possibility of permitting the fuel to escape through an open jet.

Having thus described the invention what we claim and desire to secure by Letters Patent is—

1. In a device of the class described, the combination of a receptacle, with a fluid inlet and a fluid outlet communicating with the interior of the receptacle, fluid pressure operable means located in the receptacle, liquid provided in said receptacle forming a seal between the receptacle and said means, and means for releasing the pressure in said receptacle upon the breaking of said seal.

2. In a device of the class described, the combination of a receptacle, with a fluid inlet leading to the interior of the receptacle, a fluid outlet leading from said receptacle, fluid pressure operable means located in said

receptacle, and means for producing pressure in said receptacle, said last mentioned means being controlled by said fluid pressure operable means, and means operable upon the movement of said fluid pressure operable means beyond a predetermined position, for releasing the pressure in said receptacle.

3. In a device of the class described, the combination of a receptacle, with a fluid inlet leading to the interior of the receptacle, a fluid outlet leading from the interior of the receptacle, fluid pressure operable means located in the receptacle, a passage leading from the interior of the receptacle to the atmosphere, said passage and fluid pressure operable means having means whereby the pressure in said receptacle is released through the passage leading to the atmosphere when said fluid pressure operable means is moved beyond a predetermined position.

4. In a device of the character described, the combination of a reservoir, with passages leading to and from the reservoir, a motor fan connected with said passages, a receptacle, a passage connected with said first mentioned passages and terminating in said receptacle, a valve arranged at the connection of said passages, a passage leading from the interior of said receptacle, pressure operable means located in said receptacle, a switch for controlling the operation of the motor fan, said switch being controlled by said pressure operable means.

5. In a device of the character described, the combination of a receptacle, with pressure operable means located in said receptacle, a motor fan, a fluid inlet connected with the fan and terminating in the receptacle, a fluid outlet leading from the receptacle, a switch, a connection between the switch and the pressure operable means for actuating the switch when the pressure in said receptacle is reduced below a predetermined pressure to cause the actuation of the motor fan, and means for actuating the switch to cut out the motor when said pressure operable means assumes a position beyond its first mentioned switch actuating position.

6. In a device of the class described, the combination of a receptacle, with pressure operable means located in said receptacle, a motor fan, a fluid inlet connected with the fan and terminating in the receptacle, a fluid outlet leading from the receptacle, a switch, a connection between the switch and the pressure operable means for opening and closing the switch, and means operable to render the switch inoperative when said pressure operable means reaches a position beyond its normal switch opening and closing positions.

7. In a device of the class described, the combination of a receptacle, with pressure

operable means located in said receptacle, a motor fan, a fluid inlet connected with the fan and terminating in the receptacle, a fluid outlet leading from the receptacle, a switch, a connection between the switch and the pressure operable means for opening and closing the switch, and means operable to render the switch inoperative when said pressure operable means reaches a position beyond its normal switch opening and closing positions, and manually operable means for actuating the last mentioned means to restore said switch to an operative position. 10

ERNEST E. LAUN.
ROY E. TULLGREN.
